UNITED STATES PATENT OFFICE.

JOHN KARMAZIN, OF DETROIT, MICHIGAN.

RADIATOR.

Application filed May 17, 1924. Serial No. 713,882.

To all whom it may concern:

Be it known that I, JOHN KARMAZIN, a citizen of the United States, residing in Detroit, county of Wayne, State of Michigan, have invented certain new and useful improvements in Radiators, of which the following is a specification.

This invention relates to radiators, and is illustrated in the drawings and will be herein described as applied to a radiator of the type disclosed in my prior copending application Sr. No. 579,416, filed August 3, 1922. The radiator described in said application comprises a number of horizontally disposed fin forming elements, each having integral therewith tapering tubular projections which telescope into the open ends of similar tubular projections on the next lower element, thereby forming a plurality of tubes extending vertically from top to bottom of the radiator. The tubes on the bottom element extend into the lower header and water circulates thru the tubes from the upper to the lower header.

It will be seen that in this construction, which is more fully described in my application above mentioned, the space surrounding the tubes projecting from the bottom element into the lower header forms a trap or pocket in which steam may accumulate.

One object of the present invention is to provide a radiator of the type described with means for preventing such accumulation of steam in the lower header.

A further object of this invention is to provide a radiator with means in communication with the top of the lower header for permitting the escape of steam therefrom.

A further object of this invention is to provide a radiator comprising water circulating tubes with specially constructed steam escape tubes.

A further object of this invention is to provide a radiator comprising an upper header and a lower header, with two sets of tubes extending between the headers, the tubes of one set terminating at a different level in one or both of said chambers from the tubes of the other set.

A further object of this invention is to provide a radiator comprising tubes extending between upper and lower chambers or headers with auxiliary devices associated with certain of said tubes and projecting into said upper chamber.

With these and other objects in view my

invention consists in the novel combinations and arrangements of parts illustrated in the drawings, and to be hereinafter described.

In the drawings:

Figure 1 is a vertical section of a radiator embodying my invention.

Figure 2 is a detail elevation in section showing an auxiliary tube extending into the upper header.

Figure 3 is a detail elevation in section showing a modified form of my invention.

The radiator to which I have applied my invention for purposes of illustration comprises a plurality of fin forming elements 10, each formed with a plurality of tapering tubular projections 11, surrounded by perforations in the fins, the projections of one element extending a short distance into the projections on the next lower element, thereby forming continuous tubes extending from the upper header or chamber 13 to the lower header or chamber 12. The upper chamber comprises a curved top wall 14 and is closed by cap 141. For the purpose of securing proper circulation of air about the water tubes the intermediate elements 10, are perforated as shown at 15 (Figure 2). The top element 101 forms the bottom of the upper chamber, while the bottom element 102 forms the top of the lower chamber.

The construction thus far described is substantially similar to that disclosed in my prior co-pending application above identified. It will be seen that the projections 11, on the bottom element 102 extend a short distance into the lower chamber. Steam formed from the circulating water may rise into the space surrounding these tubes, accumulate there and retard the circulation and cooling of the water in the radiator, and the radiation of heat from the lower header. For the purpose of preventing such accumulation of steam and permitting escape of the steam from the top of the lower chamber to the upper chamber, the following devices are provided.

In the form of my invention illustrated in Figures 1 and 2 the bottom element 102 is specially formed, certain of the projections 11 are cut off, leaving perforations 16, or the element is formed with perforations in place of the tubes. The perforations 16 receive the ends of the corresponding projections on the first intermediate element 10.

This forms a plurality of openings flush with the top of the lower header so that the steam cannot pocket between the top of this header and the bottom of the tubes 11 5 projecting thereinto but may escape into the tubes 17 which communicate with the openings 16 and rise to the upper header.

To facilitate the delivery of the steam rising through the special tubes 17 to the upper 10 chamber, said tubes may be provided at their upper ends with tubular extensions 18, which project above the normal water level in the upper header, and prevent the water from flowing downward therethrough. 15 These extensions are preferably formed separately, inserted into the special tubes 17 and secured thereto by any desired means.

In the modification shown in Figure 3 an auxiliary tube 181 extends from a point 20 above the normal water level in the upper chamber, thru a special perforation in element 101 and thru a column of the perforations 15 in the intermediate elements 10, terminating in a perforation in the bottom element 102. The use of this construction obviates the necessity for using a specially prepared bottom element.

My invention is not to be considered as limited to the specific embodiment herein 30 described and illustrated in the drawings but is to be construed as extending to all equivalent devices falling within the scope of the appended claims.

I claim:

35 1. A radiator comprising a lower chamber and an upper chamber, the bottom wall of the upper chamber and the top wall of the lower chamber each being flat and two sets of tubes extending between said chambers 40 and projecting therein and terminating respectively at different levels in each chamber.

2. A radiator including a lower chamber having water circulating means projecting therein, and other means connected therewith and terminating flush with the wall thereof and extending to a point above the normal water level of the radiator whereby the escape of steam is permitted.

3. A radiator element comprising perforations surrounded by tubular projections and adapted to receive the free ends of similar tubular projections, and other perforations adapted to receive the free ends of tubular projections but not surrounded by tubular 55 projections.

4. A radiator comprising a pair of chambers, tubes connecting said chambers and projecting into one of said chambers, while terminating flush with the walls of the other 60 chamber and other tubes connecting said chambers and projecting into the other of

said chambers while terminating flush with the wall of the first chamber.

5. A radiator comprising an upper chamber and a lower chamber, tubes connecting said chambers and terminating flush with the wall of the upper chamber and projecting into said lower chamber, and other tubes connecting said chamber and terminating flush with the wall of the lower chamber and 70 projecting into said upper chamber.

6. A radiator comprising an upper chamber, a lower chamber, tubes extending between said chambers and tube extensions applied to certain of said tubes and extending 75 into said upper chamber.

7. In a radiator of the type described an upper header, a lower header, a plurality of tubular passages extending from the upper header to the lower header and terminating at different levels, the tubes of one level adapted to conduct a liquid in one direction between the headers and the tubes of the other level adapted to conduct a gaseous fluid in the other direction. 80

8. The method of venting a radiator of the type in which the water tubes project into the lower header which comprises permitting steam or the like to escape from the top of the lower header to a point above the 85 normal water level of the radiator.

9. A radiator of the type described comprising an upper chamber, a lower chamber, and a core comprising a plurality of fin members with integral tubular projections 90 extending in the same direction therefrom, the tubular projections of one fin extending into the tubular projections of the adjacent fin to form water conduits through the core and the tubular projections of the terminal 100 fin projecting into one of said chambers, and means terminating flush with the wall of said chamber for permitting the escape of steam therefrom.

10. A radiator of the type described comprising an upper chamber, a lower chamber, and a core comprising a plurality of fin members with integral tubular projections extending in the same direction therefrom, the tubular projections of one fin extending 105 into the tubular projections of the adjacent fin to form water conduits through the core, and the tubular projections of the lower fin extending into the lower chamber, and means extending through said core and terminating flush with the wall of said lower 110 chamber for permitting the escape of steam therefrom.

In testimony whereof I have affixed my signature to this specification.

JOHN KARMAZIN.
